COMBINED LAMPPOST AND MAILBOX
SUPPORT

John H. Hagen, Canton, Ohio

Application January 19, 1953, Serial No. 23,190

Term of patent 14 years

(Cl. D48—31)

To all whom it may concern:

Be it known that I, John H. Hagen, a citizen of the United States, residing at Canton, in the county of Stark and State of Ohio, have invented a new, original, and ornamental Design for a Combined Lamppost and Mailbox Support, of which the following is a specification, reference being had to the accompanying drawing, forming part thereof.

Fig. 1 is a front elevational view of a combined lamppost and mailbox support, showing my new design;

Fig. 2 is a side elevational view thereof, and

Fig. 3 is a cross sectional view taken on the line 3—3, Fig. 1.

The dominant features of my design are shown in solid lines and the dotted lines indicating a mailbox are for illustration purposes only.

I claim:

The ornamental design for a combined lamppost and mailbox support, substantially as shown and described.

JOHN H. HAGEN.
